Willard Beckley

WITNESS:

UNITED STATES PATENT OFFICE.

PETER H. KLEIN, OF TRENTON, NEW JERSEY.

RESISTANCE HEATER.

Application filed September 25, 1922. Serial No. 590,429.

To all whom it may concern:

Be it known that I, PETER H. KLEIN, a citizen of the United States, residing at Trenton, in the county of Mercer and State 5 of New Jersey, have invented new and useful Improvements in Resistance Heaters, of which the following is a specification.

My invention relates to electric heaters and more especially to electric heaters adapted to be used for heating liquid fuel preparatory for use in internal combustion engines commonly used in automobiles.

One of the objects of my invention is to provide an apparatus and means therein, by 15 which fuel oil such as gasoline or any other suitable fuel adapted for use in internal combustion engine may be heated preparatory to its introduction into a carburetor on engine for better conditioning the fuel for 20 explosion in the engine. The accomplishment of this object is desirable, because during cold weather there is at times difficulty experienced in starting an internal combustion engine, resulting from the fact that the 25 explosion chamber of the engine is too cool to permit a proper explosion of the fuel or fuel gas to take place upon its initial introduction into the explosion chamber. To overcome this difficulty it has been found 30 desirable to heat the fuel oil before its introduction into the explosion chamber and to efficiently accomplish this I have provided an electrical heater, operating by resistance that is of simple construction and of few 35 parts which can conveniently be installed in any usual form of motor car, and which has advantageous results which may hereinafter appear.

Referring to the drawings in which like 40 numerals of reference indicate corresponding parts;

Fig. 1 is an elevation partly in section of my heater enclosed in a casing in operative relation to the fuel container.

Fig. 2 is an enlarged detailed cross sectional view of the heater box or chamber and heating coil.

Fig. 3 is a top view of the heater box with the fuel container removed, showing 50 the arrangement of the resistance coil in the box.

Fig. 4 is a top plane view of Fig. 1 showing the formation of an annular ring like lid for closing the end of the casing.

Fig. 5 is a side view in detail showing the

arrangement of a coiled feed pipe placed around an exhaust for auxiliary heating of the fuel.

Referring more particularly to the drawings, my device consists of a substantially 60 cylindrical casing 1 closed at the bottom and with a top open end for which is provided a suitable annular cover 2. The casing 1 has oppositely diametrically disposed enlarged portions 3 and 4 while the lid 2 is 65 provided with similarly disposed and shaped portions to cover the portions 3 and 4 of the casing and to provide lugs through which bolts or other suitable fastening means extend to hold the lid in closed operative relation to the casing. A central 70 aperture 5 is provided in the base portion of the casing to admit therethrough a threaded electrical conductor 6 by which electrical current is carried to the heating apparatus 75 within the casing 1. Within the casing 1 there is enclosed either wholly or in part a fuel container 7 of a substantially cylindrical shape provided with lug like extensions 8 at its base and a suitable top cover 80 9. From the top 9 there is provided an outlet 10 which carries the fuel oil or gas to the engine and an inlet 11 by means of which the fuel container 7 is supplied with fuel oil from the main supply tank (not shown). 85 Beneath the container 7 I provide a heater case or chamber 12 of cross sectional shape and size substantially similar to that of the fuel container. This case or chamber 12 is provided at its base with lugs 13 and 14 90 similar to the lug 8 at the base of the fuel container. The lugs 8 are provided with apertures 15 while the lugs 13 and 14 are provided with similar apertures 16 which are adapted to register with each other and 95 receive bolts 17 provided with nuts 18 by means of which the fuel container and heater chamber are firmly held in operative relation to each other. The bolts 17 further extend downwardly through apertures 19 in the casing 1 and by means of nuts 20 hold the casing in assembled relation with the heater 100 12 and container 7 as shown in Fig. 1. The casing 1 and heater chamber 12 and fuel container 7 may be made of any suitable material preferably brass or bronze, for reasons well known in the art. The heater chamber 12 is provided with an inner lining 21 of asbestos, to prevent the radiation of 105 heat from the chamber in directions other 110

than that toward the bottom of the fuel container 7. Upon this asbestos lining on the base of the heater chamber 1 I provide a spirally wound resistance coil 22 of iron or any suitable material affording the proper amount of resistance to the passing of an electric current, to produce the desired heat. Each turn of the winding of this coil is covered with a substantially thick coating or 10 layer of asbestos 23 to act as an insulation to continue the resisting conductivity of the coil. The outer end of the coil is connected to a gripping contact plug 24 which passes through an aperture 25 in the casing 1 and 15 is suitably held therein and in a corresponding aperture 26 in the heater chamber by nuts or other suitable fastening means 27. This connecting plug 24 is provided at its outer end with locking or contact nuts 28 20 threaded on the plug adapted to make electrical connection with a conductor 29 leading thereto from a storage battery or other suitable source of electrical energy. The other or inner end of the spiral resistance 25 coil 22 is securely held in electrical connection with the head 30 of the connecting plug or contact 6, heretofore referred to as passing through the central portion of the base of the heater chamber 12 and outer casing 1. 30 The plug 6 is provided on a threaded portion which extends through the heater chamber and the base of the outer casing with an insulating washer 31 and a metallic electrically 35 conducting nut or washer 32 between which latter and a nut 33 threaded on the contact plug 6 another conductor 34, may be securely held in electrical contact therewith. The conductor 34 may lead from a storage 40 battery or other suitable source of electrical energy and so supply electrical energy to the resistance coil 22.

For the purpose of better protecting the fuel container 7 from cooling contact with the outside atmosphere I provide the casing 45 1 with a suitable thick inner layer of asbestos which will tend to retain the heated air within the casing 1 at an even temperature for a reasonably long period.

Between the main fuel supply tank or container (not shown) and the container 7 or inlet 11 therefor I install a connecting or feed pipe 35 which will supply fuel to the container 7 from the main supply tank (not shown). This pipe 35 is, in an intermediate 50 portion, provided with a section which might properly be called a return coil section 36 which is of any suitable or desired length and which is closely positioned around the outer surface of a portion of the exhaust pipe 37 of the engine (not shown).

It will be seen from the foregoing description that by providing a casing 1, I retain as much as possible of the heat within the heater chamber 12 and around the fuel container 65 7, because of the annular lid 2 which closes

the opening at the top of the casing 1. Within the casing 1 it will be seen the fuel container 7 and heater chamber 12 are assembled in a substantially unitary relation one above the other, and that by this means 70 a very compact arrangement and structure is provided. It will also be understood that when it is desired to start the engine, the electric current is turned into the resistance coil 22 in the well known way of producing 75 heat by electrical resistance, becomes hot and thereby radiates heat to the container 7 which in turn transmits this heat to the fuel oil contained therein and which will as desired pass out through the outlet 10 to 80 the combustion chamber of the engine (not shown). It is apparent that the fuel oil will thus be delivered to the combustion chamber of the engine in a heated condition, where therefore, a more certain and efficient explosion will take place, even though the chamber of the engine may be in a cold condition, as the result of atmospheric temperature or some other cause. By this means I obviate the necessity which has frequently arisen, 85 when a combustion chamber of an engine is cold, to turn the engine over one or more times and thereby put it in a more or less suitably heated condition, for ready explosion. It will be apparent that in overcoming this necessity by the provision of these means that I have added greater efficiency and convenience to the operation of an internal combustion engine in the initial starting especially under conditions where the combustion chamber is cold. 90

Having started the engine I provide means whereby the constant inflow of fuel oil into the combustion chamber will be at a suitably warm temperature to permit certain and efficient combustion; and means which after the engine has been stopped for a comparatively short period will enable the fuel oil to be introduced into the combustion chamber at a suitable temperature upon the re-starting of the engine. This latter means is that referred to as the pipe 35 and the return coil section 36 thereof, disposed around the exhaust pipe 37 of the engine. 105 It will be apparent that as the engine is operated and exhausts, the heat from the exhaust pipe 37 will be absorbed by the return coil section 36 and the fuel oil passing therethrough to the container 7 and the engine (not shown), and that this constant absorption of heat from this source will so heat the passing oil that it will be delivered to the combustion chamber of the engine at a suitable temperature to insure certain combustion. 110

From the foregoing it will be seen that my heating apparatus will therefore be adapted to the heating of fuel oil for the initial introduction into the combustion chamber of an internal combustion engine, 115 120 125 130

in proper condition to insure its initial starting, even though the chamber be cold, and to further insure the introduction of fuel oil in a proper condition for positive re-
5 starting of the engine after it has been temporarily stopped. The former heating as before stated is affected by the resistance coil 22 acting on the fuel container 7 while the latter heating is affected by the heating
10 of the exhaust pipe 37 and its acting on the return coil section 36 of the pipe 35.

It is obvious therefore that the novel means provided in my heating apparatus and system are positive in operation simple in construction and arrangement and are of such compact form and few parts that they are not readily dis-organized and can be conveniently installed in any usual form of vehicle operated by an internal combustion
20 engine and that they may have other advantages and results not specifically herein set forth.

Although I have shown and described one form of the embodiment of my invention
25 yet I do not wish to be limited thereby, for it is obvious that changes may be made in the arrangement, organization, construction

and relation of parts thereof without departing from the scope of my invention.

Having thus described my invention what
30 I claim as new and desire to secure by Letters Patent is;

In a device of the character described the combination of a substantially cylindrical hollow casing, a heat insulating lining within said casing, a fuel oil container encased in and spaced apart from said casing, means to supply fuel to said container, means to conduct fuel from said container, an annular lid surrounding said container and closing the open end of said casing, a heater chamber encased in said casing and detachably supporting said container thereon, a heat and electrical insulating lining within said heater chamber, an electrical resistance element within said heater chamber, terminal contacts engaging the opposite ends of said resistance element and electrical conductors, connected to said terminal contacts and to a source of electrical energy, adapted thereby to heat said resistance member and the contents of said container.

In testimony whereof I affix my signature.
PETER H. KLEIN.
